UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

FOURTH-POINT SUPPORT FOR BRAKE-BEAMS.

1,304,134.

Specification of Letters Patent.

Patented May 20, 1919.

Application filed February 25, 1918 Serial No. 219,005.

To all whom it may concern:

Be it known that I, CHARLES HAINES WILLIAMS, a citizen of the United States, residing at the city of Chicago, county of 5 Cook, and State of Illinois, have invented a certain new and useful Improvement in Fourth-Point Supports for Brake-Beams, of which the following is a full, clear, and exact description, such as will enable others 10 skilled in the art to which it appertains to make and use the same, reference being had to the accompanying drawings, forming part of this specification.

Figure 1 is a conventional plan view of a 15 brake beam showing my improved fourth point support.

Fig. 2 is a vertical sectional view through one of the supports.

Fig. 3 is a side elevational view of the 20 form of support shown in Fig. 2.

Fig. 4 is a detail view of a modification.

Fig. 5 is a cross sectional view of the 25 modification shown in Fig. 6.

Fig. 6 is a side elevational view of the 30 modification shown in Fig. 5.

Figs. 7 and 8 are end and side elevational views of another modification.

Fig. 9 is a cross sectional view of another 35 modification.

Figs. 10 and 11 are end and side elevational views of another modification.

This invention relates to new and useful 40 improvements in fourth point supports for brake beams, the object being to obviate the necessity for the use of right and left hand castings and to enable the use of malleable, wrought iron, steel, pressed or rolled parts, whereby the proper support or chair may be provided for securing in position the support.

These fourth point supports are frequently applied to the brake beams after the beams are assembled and it has been found to be practically impossible to use gray iron castings which have been formed with their 45 wings sufficiently opened to slip over the tension rod as when said wings are closed they are liable to break.

It is therefore proposed that the sliding portion of the chair be made of the casting 50 which is fastened or secured to the tension rod, truss rod, or other fixed part of the

beam by wrought, malleable, rolled or pressed steel bands which are interchangeable in that they are capable of use on the right and left side of the beam.

55

In Fig. 1 of the drawings, I have shown diagrammatically a brake beam having fourth point supports in which 1 indicates the compression member, 2 the tension member, 3 the strut, 4 the brake heads, 5 the 60 tracks for the fourth point supports, and 7 the spring plank or part of the truck to which the tracks for the fourth point supports are connected.

8 indicates the bracket embracing the tension rod which bracket is formed with an opening in its lower portion which opening receives a teat 9^a, the casting or stirrup 9 forming a rubbing or wearing surface. This casting is provided with a saddle for receiving the tension rod which saddle carries the teat 9^a and under the saddle is the wearing shoe.

65

In Fig. 4, I have shown a similar construction in which the stirrup 9^c is in the 70 form of a semi-sphere.

In Figs. 5, 6, 7, and 8, I have shown modified forms in which the parts 10, 11, 13 and 14 are hinged together. In Figs. 5 and 6, a pintle 15 is employed while in Figs. 7 and 80 8 a detachable hinge connection is shown.

In Fig. 9, 19 indicates a clamp embracing the tension member and confining the wearing shoe 20 in position.

In Figs. 10 and 11, there is a malleable 85 casting 21 clamped on the tension rod for holding a roller 22 in place.

It will be readily understood, of course, that still other modifications and adaptations of my improved fourth point support 90 for brake beams may be made without departing from the spirit and scope of what I claim to be my invention.

What I claim is:

1. The combination with a supporting 95 part of a brake beam, of a clamping member, and a separable supporting member supported in position by said clamping member and held against vertical and lateral movement thereby.

100

2. The combination with a supporting part of a brake beam, of a clamping mem-

ber composed of nonfrangible material, and a separable supporting member supported in position by said nonfrangible part and held against vertical and lateral movement thereby.

3. In a brake beam fourth point support, a supporting member attached to the brake beam by a separable member and held against vertical and lateral movement and

capable of attachment to either the left or 10 righthand side of the beam.

In testimony whereof I hereunto affix my signature this 9th day of February, 1918.

CHARLES HAINES WILLIAMS.
